Attorney

United States Patent Office.

N. S. WHIPPLE, OF DETROIT, MICHIGAN.

Letters Patent No. 95,622, dated October 5, 1869.

IMPROVED SPRING FOR BEDS, BERTHS, CAR-SEATS, &c.

The Schedule referred to in these Letters Patent and making part of the same.

To whom it may concern:

Be it known that I, N. S. WHIPPLE, of Detroit, in the county of Wayne, and State of Michigan, have invented certain new and useful Improvements in Spring-Seats for Cars, Berths, Beds, &c.; and I do hereby declare that the following is a full, clear, and exact description of the same, reference being had to the accompanying drawing, and to the letters of reference marked thereon, making part of this specification, in which—

Figure 1 is a top view of a frame with my spring-seat attached, and covered with wire-cloth or gauze.

Figure 2 is a reverse view of a frame with my spring-seat attached.

Figure 3 shows the springs, interlocked by a continuous wire.

Figure 4 shows the springs, connected by independent hook-wires.

The nature of my invention consists in securing to rods, so connected as to form a frame, a series of coiled springs, said springs being interlocked one with the other, by means of a continuous wire, or otherwise connected by means of short independent wires, which are provided with hooked ends.

The advantages of this arrangement are readily discernible.

The springs being connected as they are, any pressure upon the same is equalized, thus preventing the strain being concentrated on a single spring, and besides, the springs are so interlocked that a greater degree of elasticity is afforded. Also, the springs and their connections being all of metal, a degree of durability is insured that is possessed by no other spring.

To enable others skilled in the art to make and use my invention, I will now proceed to describe its construction and operation.

A is a rectangular frame, and may be either the

fixed seat of the chair, bed, or berth, or an independent frame, to be secured thereto.

To this frame I secure, by means of eye-bolts *a a*, the rods *A' A'*.

Around these rods *A' A'* are coiled springs *B B*.

These springs *B B* are so secured to the rods *A' A'* as to form loops *b b*, said loops extending out toward the centre of the frame *A*.

The springs *B B* are connected together by a continuous wire, *C*, said wire being so bent as to form a series of tongues, *c c*.

Over these tongues *c c* pass the looped ends *b b* of the springs *B B*.

The springs *B B* are thus all firmly and securely attached together, but at the same time are so connected that the utmost freedom in operation is allowed. The arrangement, as well as the connection, is clearly shown in fig. 3.

Instead of connecting the springs *B B* by the continuous wire *C*, they may be secured by independent wires *D D*, each having hooked ends *d d*, by means of which they are secured to the looped ends *b b* of the springs *B B*.

Having thus fully described my invention,

What I claim therein as new, and desire to secure by Letters Patent of the United States, is—

The combination of the springs *B B*, the continuous wire *C*, or independent wires *D D*, the whole being so arranged as to operate substantially as described.

In testimony whereof, I have signed my name to this specification, in the presence of two subscribing witnesses.

N. S. WHIPPLE.
